UNITED STATES PATENT OFFICE.

ANTOINE LACROIX, JR., OF BROOKLYN, ASSIGNOR TO THE CO-OPERATIVE BUILDING PLAN ASSOCIATION, OF NEW YORK, N. Y.

DESIGN FOR THE EXTERIOR OF A RESIDENCE.

SPECIFICATION forming part of Design No. 19,565, dated January 7, 1890.

Application filed December 9, 1889. Serial No. 333,666. Term of patent 3½ years.

To all whom it may concern:

Be it known that I, ANTOINE LACROIX, Jr., of the city of Brooklyn, in the county of Kings and State of New York, have invented and produced a new and original Design for the Exterior of a Residence, of which the following is a specification, reference being had to the accompanying drawings, forming a part thereof.

10 Figure 1 represents a perspective view of a residence showing my design. Fig. 2 represents a horizontal section or plan of the first story. Fig. 3 represents a horizontal section or plan of the second story.

15 Similar letters of reference designate corresponding parts in all the figures.

A residence embodying my design comprises a first and second story and an attic story. "L's" extend from both sides of the 20 residence. At the front of the first story is a bay A, which has a doorway c. The bay A is substantially octagonal in shape. At the front and surmounting the bay A is a porch B, of substantially the same shape as the bay 25 A. A flight of steps b leads to the porch B. Above the flight of steps b is a gable roof C. Pillars e extend between the roof C and the porch B. At one side of the residence is an L D, having a substantially flat side. At the 30 other side of the residence is an L E, also having a substantially flat exterior. At the

rear of the residence is an extension G, which extension is provided with a gable roof G'.

The second story of the residence, at the front, is provided with a rectangularly-shaped bay H, substantially above the roof C upon the porch B. The L E at the second story is shown as having an oriel-shaped bay I. Above the oriel-shaped bay I and at the attic story there is an overhanging gable J. Consoles d 35 extend between the overhanging gable J and the end of the L E at the sides of the oriel I. Upon one of the slopes of the gable J are two dormer-windows K L, the former being surmounted by a gable roof and the latter having a shed roof. The window L is smaller, as shown, than the window K. The front portion of the attic story is surmounted by a curb-roof M and somewhat overhangs the second story. Consoles j extend between the 40 overhanging portion of the roof M and the front, said consoles being shown as at the sides of the bay H. The L D is surmounted by a gable roof N.

What I claim is—

55 The design for the exterior of a residence, substantially as herein shown and described.

ANTOINE LACROIX, JR.
